E. BRONNERT

HIGH SPEED MOTOR DRIVEN SPINDLE

Filed Oct. 5, 1925

UNITED STATES PATENT OFFICE.

EMILE BRONNEBT, OF STRASSBURG, FRANCE.

HIGH-SPEED MOTOR-DRIVEN SPINDLE.

Application filed October 5, 1925, Serial No. 60,636, and in France July 15, 1925.

It frequently happens in various machines that a spindle arranged vertically rotates at very high speed driving a tool or other device mounted on its upper part. This is the case, 5 for example, in the spindles of polishing bobs, twisting frames and other such machines or apparatus.

It is known that such spindles, thus arranged vertically and to which a high speed 10 of rotation is imparted, are subjected to vibration, particularly if the device which they drive is of fairly considerable mass. This vibration, the injurious effects of which are well known to engineers, (wear, distortion and 15 even breakage), is due to the fact that the axis of gyration of the whole system (comprising the driven spindle and the tool or other mass which it drives) does not coincide with the axis of rotation of the spindle itself.

20 This invention has for its object to provide an improved arrangement for mounting these spindles or shafts which overcomes the disadvantage above referred to. A further object is to provide an improved spinning centrifuge, that is to say, a centrifugal machine 25 for driving vessels (known as "spinning pots" or "turbines") which serve to store artificial textiles. Another object is to provide improved suspension means for such 30 machines, permitting the spinning vessels to be rotated at a much greater speed than at present while yet ensuring the usual twist of from 100 to 120 revolutions per metre and 35 avoiding the vibrations which are so injurious to the quality of the thread produced.

In carrying my invention into practice I provide the driving rotor, mounted for rotation in the body of the motor with a hollow bore, in which the spindle is arranged, said 40 spindle extending through such bore and being connected to the rotor at one end by a driving connection such that when running it can deviate slightly from its normal position in relation to the rotor and set itself 45 freely in the axis of gyration of the rotating system in which it is included. Preferably the motor body or casing, as a whole, is carried in a Cardan or like yielding suspension. The spindle passes freely and co-axially 50 through the hollow rotor shaft to the driving connection and is either sufficiently elastic in itself, or is connected to the hollow shaft of

the rotor by devices which are sufficiently elastic to permit of its necessary slight movement within the hollow rotor shaft. 55

This movement, combined with the self-righting faculty possessed by the whole system, (by reason of the Cardan suspension of the stator) has the effect of permitting the spindle to set itself freely along the axis of 60 gyration of the system (exactly like a top). This avoids the vibrations which derive from the unbalanced periodic reactions.

Various subsidiary features of my invention are hereinafter particularly described 65 and set forth also in my statement of claim.

In the accompanying drawing is shown, diagrammatically a preferred constructional form of apparatus according to my invention, the drawing showing an axial section through 70 the whole device.

Referring to this drawing; the numeral 1 designates a casing, in which is fixed a small electric motor constituted by a stator 2, fixed to the said casing, and a rotor 3. 75

The rotor 3 has a hollow shaft 4, which is centred in ball bearings 5, 6. Through the interior of the shaft 4 of the rotor passes the spindle 7, on the end of which is fixed the tool or apparatus which is to be driven with a rapid rotary movement, as for instance, a 80 polishing bob or a spinning pot.

At its lower part the spindle is connected to the hollow shaft, through which it passes freely, by a flexible or elastic member 8, 85 which allows it a certain amount of play.

At the upper part of the apparatus another elastic member 9 serves to centre the spindle relatively to the rotor.

In the mode of carrying out the invention 90 illustrated in the drawing the devices 8 and 9 are each constituted by a hollow symmetrical revolving body, preferably of cylindrical or conical form, which hollow body has walls which are thin enough to possess a certain 95 amount of elasticity. Furthermore, the walls have slots 10 in them, which subdivide them into strips 11, so as to add still more to the elasticity of this device.

At the lower end, one of the bosses 12 of 100 the hollow body is fixed to the spindle 7, for example, by means of a clamping screw 13, which grips a shoulder 14. The other boss 15 is rigidly attached to the hollow shaft 4, by

means of a clamping screw 16, for example.

In the elastic device 9, which serves to guide the spindle in the rotor at the top end one of the bosses 17 of the device is rigidly 5 connected to the rotor or to the body of the motor. Through the other boss 18 passes the spindle 7, which is adapted to rotate freely in a ball bearing (not shown in the drawing).

In order to increase the capacity of the 10 system for automatic centering, it is desirable to suspend the body from a Cardan suspension. In the drawing numerals 19 designate a pair of trunnions fixed at diametrically opposite points on the casing 1 and taking their 15 bearing in a ring 20. This ring 20 is itself provided with trunnions 21 arranged in the same horizontal plane as the trunnions 19 but at right angles to the latter and these trunnions 21 take their bearing in the outer 20 Cardan ring member 22. It will be understood that with such device the spindle becomes self-centering and rotates without vibration and without axial or radial shake about the gyroscopic axis of the system.

25 Actually the foot of the spindle can move slightly under the reacting forces and, consequently, it sets itself in such a position that the periodic reactions are zero or counterbalanced.

30 With spindles of the type described speeds of 7000 to 8000 revolutions per minute can be obtained, whereas with a plain spindle of stout construction, whether mechanically or electrically driven, not more than 5000 to 35 6000 revolutions per minute, could be attained. Furthermore, a spindle revolving without vibration at higher speed, can absorb more metres of the thread ejected by the spinning head and conveyed by the well known feed roller, whilst always ensuring the usual amount of twist. The efficiency of the spindle is thus increased. The higher speed also develops a greater centrifugal force and permits of winding up the fine and coarse counts 40 for which purpose, hitherto only a bobbin could be employed.

45 What I claim is:—

1. In a high speed rotary machine, a casing 50 having a stator element therewithin, a rotor element provided with a hollow shaft antifrictionally mounted for rotation in said casing, and a spindle member fixedly connected at one end to an extremity of the hollow shaft and extending from said point of connection through said hollow shaft and beyond the other extremity of the latter to a point of 55 attachment to a load to be rotated, the combination of hollow shaft and spindle member including resilient guide means for the spindle permitting deviation thereof in relation to said shaft.

60 2. In a spinning centrifuge a vertical spindle, a spinning vessel carried on the top end thereof, a casing surrounding said

spindle, stator parts within said casing and a 65 rotor having a hollow shaft journalled in said casing, said spindle being located freely within said hollow shaft and having its lower end united to the lower end of said shaft.

3. In a high speed rotary machine, a vertical casing having shaft bearings in its upper and lower ends and stator parts located intermediate its ends, a hollow rotor-carrying shaft antifrictionally journalled in said bearings, a vertical spindle extending 70 through the bore of the shaft for carrying a rotating load, and means connecting said spindle to said shaft in yielding centering position therewithin at the end remote from the load.

4. An apparatus according to claim 3, having means for resiliently guiding the vertical spindle at a point spaced from the end of the hollow shaft through which the former projects.

5. An apparatus according to claim 3, having an elastic spindle guide member spaced from and supported by the hollow rotor shaft through which the spindle extends.

6. In a high speed rotary machine, a vertical casing having shaft bearings adjacent its upper and lower ends and stator parts located intermediate its ends, a hollow rotor-carrying shaft journalled in said bearings, resilient members mounted on the two ends 90 of the hollow shaft and a vertical spindle extending through the bore of said hollow shaft, said spindle having one of its ends secured fixedly to one of the resilient members while the other resilient member embraces 95 and guides said spindle intermediate its ends.

7. In the apparatus of claim 6 a resilient member consisting of a hollow symmetrical body with thin elastic walls and having a 105 boss to engage the hollow rotor shaft and a second boss bored to embrace the vertical spindle substantially as specified.

8. In a high speed rotary machine the combination with a vertical casing and a Cardan suspension therefor of stator parts fixed in the casing, a rotor journalled for rotation in the casing, a vertical spindle and a driving connection between the rotor and the spindle, such that said spindle can, in rotating, execute a limited gyratory movement.

9. In a spinning centrifuge a vertical spindle, a spinning vessel carried on the top end thereof, a casing surrounding said 110 spindle, stator parts within said casing a Cardan suspension for said casing and a rotor having a hollow shaft journalled in said casing, said spindle being located freely within said hollow shaft and having its lower end united to the lower end of said shaft.

10. In high speed rotary machine, a vertical casing, a Cardan suspension means therefor, shaft bearings adjacent the upper

and lower ends of said casing and stator parts to one of the resilient members while the intermediate said bearings, a hollow rotor- other resilient member embraces and guides carrying shaft journalled in said bearings, said spindle intermediate its ends. 10
resilient members mounted on the two ends
5 of the hollow shaft and a spindle extending Signed at Strassburg, France, this 21st day through the base of said hollow shaft, said of September, 1925.

DR. EMILE BRONNERT.
